UNITED STATES PATENT OFFICE.

WILLIAM R. JEAVONS, OF CLEVELAND, OHIO.

WINDOW FOR STOVES.

1,208,789.

Specification of Letters Patent. Patented Dec. 19, 1916.

Application filed June 11, 1913. Serial No. 772,987.

To all whom it may concern:

Be it known that I, WILLIAM R. JEAVONS, a citizen of the United States, residing at Cleveland, in the county of Cuyahoga and State of Ohio, have invented a certain new and useful Improvement in Windows for Stoves, of which the following is a full, clear, and exact description, reference being had to the accompanying drawings.

10 This invention relates to windows for stove drums or similar inclosures for burners and particularly for the burners of oil stoves. As usually constructed, these windows are made of mica or similar transparent material, whereby an inspection of the burner and of the flame is permitted, enabling the operator to adjust the wick so as to secure the height of flame that may be desirable or necessary. The windows of this 15 type are objectionable for the reason that they subject the eye of the observer to the bright white light of the flame, producing fatigue and strains injurious to the eyesight. They are further objectionable for the reason that the mica or similar transparent material is not durable, being extremely liable to breakage and injury.

It is the object of this invention to provide a window of this character which will 20 not be liable to breakage and injury under ordinary conditions of use, which will permit an inspection of the flame, and which will at the same time serve to break up the light rays proceeding from the flame in such 25 manner as to practically cut out the rays which produce the undesirable strains upon the eye, while not interfering with the proper functioning of the burner. In practice, I secure this result by employing in the 30 construction of the window a covering of foraminous material such as wire gauze, having such dimensions of wires and such mesh as will produce the desired effect upon the light while not admitting a draft of air 35 in such quantity as to detrimentally affect the draft conditions within said drum, as these would result in the production of carbon monoxide which, in a stove or heater having no flue connection, would necessarily 40 be discharged into the room to the serious 45 injury of the occupants.

With the foregoing object and with other objects to be explained hereinafter in view, the invention may be defined generally as consisting of the combinations of elements 55 embodied in the claims hereto annexed and illustrated in the drawings forming a part hereof, wherein:—

Figure 1 illustrates a front elevation of a portion of a stove and drum having my invention applied thereto; Fig. 2 a cross sectional detail through the window and a portion of the drum to which it is applied; and Fig. 3 a sectional view taken at right angles to Fig. 1.

Describing by reference characters the various parts illustrated herein, 1 denotes the drum base, 2 the drum, and 3 the hydro-carbon draft-burner of an oil heating stove, the aforementioned parts being of any approved construction. At a suitable height to permit of convenient inspection of the burner flame, an opening 4 is provided in the drum, said opening preferably being rectangular. This opening is shown as covered by a wire gauze screen 5, which is held to its seat across the opening by means of a sheet metal window frame consisting generally of a central countersunk reticulated backing for the gauze and an embossed outer 70 rim whereby the frame may be supported and clamped in place.

6 denotes the central countersunk portion of the frame, such countersunk portion being preferably reticulated and having a relatively large area of perforations, whereby inspection of the flame is permitted. The frame is preferably of light sheet metal, and the portion 6 is countersunk so as to form substantially a continuation of the cylindrical surface 2 of the drum. The outer portion of this frame is pressed outwardly, being united with the centrally depressed portion by a shoulder 7, and the outer edges of the outwardly pressed portion 8 are preferably beveled, as shown at 9, to present a neat appearance and to contact closely with the drum wall.

The wire gauze 5 is of such length and width as to cover the opening 4 and be 100 clamped against the edges of the opening by the portion 6 of the frame. The outer

edges of the gauze are bent outwardly, as shown at 5^a, whereby the gauze fits around the inwardly projecting portion 6 of the frame to be retained in place thereby. The 5 frame is secured to the drum, as by means of short bolts 10, the heads whereof fit in countersunk recesses 11 in the frame, nuts 12 securing the bolts and the frame to the drum.

10 By the construction described, the wire gauze covering for the opening 4 is easily applied to the frame and the frame and gauze are conveniently and effectively secured in operative relation to each other 15 and to the opening.

The frame performs a two-fold function. Where wire gauze is employed as the foraminous material, it serves as a backing for the same. The pattern with which it is provided serves the important function of increasing the obstruction offered by the foraminous material to the passage of air therethrough and thus enables me to provide the drum with a larger window opening 20 than could otherwise be employed because of the necessity of preserving the draft conditions within the drum substantially intact, while it does not prevent the 25 observation of the flame contour.

30 I have found that, by using wire of about nine-thousandths inch gage for the gauze and by employing at least fifty of these wires to the linear inch, the disagreeable light rays are eliminated and a detrimental draft through the gauze above the burner 35 flame is prevented. The most efficient results are secured when, with wires of this gage, the number per linear inch is from fifty to sixty. With this arrangement, the 40 area of perforation is about one fourth of the total area of the opening covered by the wire gauze while the openings between the wires are sufficiently small to frictionally retard the flow of the air and thus prevent 45 drafts entering the drum which will detrimentally affect the flame.

Having thus described my invention, what I claim is:—

1. The combination, with a cylindrical 50 drum having a window opening, of a frame for said opening having a perforated or reticulated central portion covering the opening and having substantially the same radius of curvature as the drum, said frame having an outer or rim portion surrounding 55 the opening and connected with the central portion by means of a ledge or shoulder, means extending through said rim and connecting the frame to the drum, and a wire 60 gauze covering for the opening having its outer edges bent around said ledge or shoulder.

2. The combination, with a drum having

a window opening in the wall thereof, of a sheet-metal frame having a depressed perforated central portion of greater area than 65 said opening and an outwardly pressed rim portion surrounding the central portion and connected thereto by a ledge or shoulder, said rim portion having its outer edges 70 bent toward the drum to contact therewith, a wire gauze covering for said opening, said covering having its edges flanged outwardly around the said ledge or shoulder of the frame, and means for securing the frame to 75 the drum.

3. The combination, with a drum having a hydrocarbon draft burner therein and a window opening for observing the burner flame, of a foraminous covering for said 80 opening, the openings in said covering frictionally retarding the passage of air therethrough, and a pattern coöperating with the covering to increase the obstruction offered by the openings therein to the passage of 85 air therethrough, the openings permitting the observation of the flame contour and being sufficiently small to materially limit the passage of light rays therethrough and to substantially maintain intact the draft 90 conditions within said drum.

4. The combination, with a drum having a hydrocarbon draft burner therein and a window opening for observing the burner flame, of a wire gauze covering for said 95 opening, the meshes in said covering frictionally retarding the passage of air therethrough, and a backing frame for the gauze having a pattern for coöperating with the gauze to increase the obstruction offered 100 thereby to the passage of air therethrough, the meshes in said gauze permitting the observation of the flame contour and being sufficiently small to materially limit the passage of light rays therethrough and to substantially maintain intact the draft 105 conditions in said drum.

5. The combination, with a drum having a hydrocarbon draft burner therein and a window opening for observing the flame of 110 said burner, of a foraminous covering for said opening, the openings in said covering permitting the observation of the flame contour and being sufficiently small to materially limit the passage of light rays therethrough and to maintain substantially intact the desired draft conditions within said 115 drum, the area of perforation being approximately one-fourth the area of the covering.

6. The combination, with a drum having a hydrocarbon draft burner therein and a window opening for observing the burner flame, of a wire gauze covering for said 120 opening, the wires of said gauze being substantially nine one-thousandths of an inch 125

in diameter, there being approximately fifty such wires to the linear inch, whereby the passage of light rays through the covering will be materially limited, the desired draft conditions within said drum will be maintained substantially intact, and the contour of the flame may be observed.

In testimony whereof, I hereunto affix my signature in the presence of two witnesses.

WILLIAM R. JEAVONS.
